UNITED STATES PATENT OFFICE

2,472,346

MILLING MACHINE FOR FORMED CUTTERS

Ernst Schindler, Biel, Switzerland

Application November 11, 1943, Serial No. 509,911
In Germany September 9, 1942

3 Claims. (Cl. 90—15)

1

My invention relates to improvements in milling machines for formed and profiling cutters, and the objects of my improvements are, first, to eliminate the manual shifting from tooth to tooth when milling cylindrical cutters and their chuck; resetting when milling the faces of the latter; and second, to provide automatically operated means for manufacturing spirally grooved formed cutters of any form, such as milling files, shank end mills, angular cutters, and counter sinks.

I attain these and related objects by the machine and appurtenant mechanisms illustrated, by way of one form of design, in the accompanying drawings, in which—

Fig. 1 is a front elevation of the machine; Fig. 2 a right-hand side view thereof; Fig. 3, an enlarged detail of Fig. 2, shows the action of the cam disk upon the setting of the vertical carriage; Fig. 4 shows details of the working spindle control; Fig. 5 is a side view of the spiral motion control of the working spindle; Fig. 6 is a front view thereof; Fig. 7 is a cutter setting diagram; and Fig. 8 is a top view of the vertical carriage, showing a series of graduated rings for setting the milling spindle eccentricity.

The embodiment illustrated comprises the machine proper 1 and the base column 2 with the oil pan 3.

The principal parts of the machine are: The bed 4, the horizontal carriage 5, and the vertical carriage 6 (Figs. 2 and 3), upon which the headstock 8 with the cutter spindle 7 may be vertically displaced. The spindle 9 with the cutter blank 10, and related parts are displaceably disposed—in a manner well known—on the cross slide 5. On the latter, furthermore, the tailstock 11 is mounted.

Two electric motors, independent of each other, drive the cutter by means of the endless belt 12 (Fig. 2) and the cam shaft 13 which extends longitudinally through the machine.

The operation of the machine is fully automatic and is effected by means of seven cam disks, which work as follows: The first cam disk drives the horizontal carriage 5; the second, denoted by 14 in Fig. 3—raises the vertical carriage 6 by means of the lever 15, to lift the cutter upon its return stroke off the blank 10, and the amount of lift is adjusted by means of the set screw 16; the third, denoted by 17 in Fig. 3—also works, over the lever 18, upon the vertical carriage 6 to mill the form or profile, for which purpose the said lever is fulcrumed at 19 to the said carriage and supported by the bearing 21

which is finely adjustable by means of the screw 20 to change the vertical stroke of the carriage according to the numbers to be read off the lever and which indicate the camming ratios; the fourth operates the working spindle control shown in Fig. 4 by means of a lever (not shown) connected with the toothed segment 22 which cooperates through the other toothed segments 23—25 to rock the arm 26 to which the spring loaded push pawl 27 is fulcrumed, and the control stroke is adjusted by the set screw 28 of the segment 24.

The pawl 27 co-acts with a dividing disk 29, which at the same time is acted on by the catch pawl 30 adapted to disengage the releasing segment 31. The stroke of the segment 24 is adjusted by the screw 28 in dependence upon the angular disposition of the recesses in the disc 29, coacting with the pawl 27.

The latter is actuated, i. e. raised or lowered, by the fifth cam disk acting upon the arm 33 (Fig. 4) and the rod 32.

The spindle control is initiated by the releasing segment 31 lifting the catch pawl 30 off the trapezoidal recess in the rim of the dividing disk 29, upon which the push pawl 27 rotates the latter forward for just one tooth. The pawl 30, then, is caught in another said recess by lowering of the arm 33. The sixth cam disk actuates the spiral motion of the working spindle. For this purpose the steel band 34 unreels off the drum 35 against the action of the helical spring 36. By shifting or displacing the point of attack of the free band end, e. g. by securing the latter to a lever, the spiral motion may be changed at will.

The unreeling of the band 34 rotates the wide pinion 37, in which the said spring 36 is housed, and this rotation is transferred onto the working spindle 9 (Fig. 6) by means of the intermediate pinion 38. This transfer is performed through the agency of the pinion pair 39—40 pivoted in the support 42. The latter may be rocked within certain limits and secured therein by the lock screw 41 so as to permit of reversing the sense of rotation of the spindle 9.

The seventh cam disk (43 in Fig. 1) actuates the bearing 44 of the eccentrically mounted milling spindle 7, in case the latter shall describe an arc in accordance with the eccentricity set. For this purpose a pinion 45, engaged by the toothed segment 46, is secured to the rear end of the said bearing 44.

Fig. 2 shows clearly how the segment 46 is rotated under the influence of the bell-shaped cam

disk 43 by way of the arms 47—50. A hinge part 51, located between the arms 48 and 49 and adjustable by displacement, permits of accurately regulating the swing of the eccentric milling spindle.

The tension roller 52, acting upon the band 34, serves for securing a precise engagement of the teeth of the dividing disk 29 by the catch pawl 30 (Fig. 5).

All cam disks keyed to the shaft 13, with the exception of the cam disk 43, are housed in the bed 4. The control devices illustrated in Figs. 4—6 are housed in the box 53, shown by dash-and-dot lines in Fig. 2. In Fig. 1 the said six cam disks are situated approximately at the points I—VI, keyed to the shaft 13.

The cam disks II, IV, and V never are taken off, while the disks I, III, and VI are mounted or demounted through the bearing covers 54 and 55 (Fig. 1). The movements then are adjusted and controlled as follows:

The eccentric cutter spindle 7 is adjusted in the following manner: In the first place, the radius R2 of the circle to be described by the cutter 57 (Fig. 7) has to be determined on the enlarged form 56 of the formed cutter. The eccentric is released by loosening the screw 58 (Fig. 8), upon which the ring 59 with the eccentricity division may be turned by means of a socket wrench until the number (reading to $\frac{1}{16}$ of a millimeter) corresponding to the desired radius lies under the pointer 60. Second, the angular amount of rotation of the spindle 7 must be ascertained, so that the cutter 57 will cover a path fixed by the measured angle ($c+d$) of Fig. 7. This is checked by means of the ring 61, provided with a circle division, which may be turned after loosening the screw 62. The value then is set by shifting the point of attack of the hinge 51 on the lever 48 (Fig. 2). Third, the spindle 7 has to be brought into its correct position, i. e. the cutter, after a revolution of c degrees, should rest on the point of culmination in the example chosen in Fig. 7, whereby the degrees are read off the division of the ring 63 and correspond to the eccentricity at hand. If the culmination has been set accurately, this number of degrees also must lie off the pointer 60. In order to permit of displacing the toothed segment 46 relative to the movement coercively transmitted by the cam disk 43, the hinge 51 is connected to the arm 49 by way of a rotatable joint 64 (Fig. 2).

The sense of spiral movement, right- or left-hand, is set by means of the support 42 (Fig. 6), and the running distance by means of the set screw 28 (Fig. 4). Care must be taken that the dog or raiser pin 65 sufficiently lift the push pawl 27. The correct engagement of the pawl 30 in the corresponding tooth is obtained, as mentioned above, by displacing the tension roller 52 for the steel band 34 (Fig. 5).

Cylindrical cutters heretofore usually have been made in the large universal milling machines, and the switching over from one tooth to another had to be done manually. In case the cutter had to be milled on its face also, a second chucking operation became necessary.

In the machine according to the present invention, the adjusting is done automatically and the face is milled in the same chuck setting.

Manufacturing on the universal milling machines known heretofore presented further difficulties in the fabrication of tapered or beveled cutters. The work piece has been rotated by change speed gears for the production of the

spiral. By such transmission, however, the work piece was rotated at a certain fixed speed, which is not correct for a tapered piece, since the peripheral speed increases with the diameter or, in other words, the pitch angle becomes greater.

The machine according to my present invention, while generally controlled in a manner known by cam disks, differs from the automatics known heretofore in that three cam disks are provided for the definition of the cutter profile, which actuate levers of variable transmission ratios and thus control the position of the milling spindle. The first of these three cam disks raises or lowers the vertical carriage on which the milling spindle is eccentrically mounted. The second actuates the horizontal carriage, and the third rotates the sleeve in which the milling spindle is eccentrically mounted. This latter or third cam disk permits of maintaining the spiral at a certain fixed angle in spite of the difference of diameters.

The manufacturing of so-called formed or profiling cutters (cherries, round-nosed or chamfered cutters, and a long line of special cutters) heretofore has presented quite a number of difficulties. Usually special machines have been built, i. e. a machine for each form. The form itself then was defined by a curve sleeve. With the cutter advancing, the curve sleeve was rotated coercively. If, now, the spiral pitch had to be changed or turned right or left, a new curve sleeve had to be made first; while in the present machine all these changes are made by means of a screw. Furthermore, the templet producing the form heretofore had to be changed with every slight change of the base form.

The latter in the present machine may be varied in relatively wide limits, since the longitudinal travel may be changed in the ratios 1:2:5, the vertical travel 1:10, and the eccentricity of the spindle from 1—10 mm. All these changes, moreover, may be made independently from each other. This feature is of marked advantage in cases where only small series of cutters have to be produced, after which bigger or smaller cutters may be made by changing any one of the said three movements.

By means of the present universal milling machine more different kinds of cutters may be produced, and this in a fully automatic way, than in any milling machine for universal cutters known heretofore.

What I claim and desire to secure by Letters Patent is:

1. In a cam controlled milling machine of the kind described, a horizontal work supporting carriage, a vertical carriage, a cutter spindle, a sleeve chuck eccentrically mounting the cutter spindle on the vertical carriage, and first, second and third cam devices for determining the position of the cutter spindle with respect to the work piece at any stage for defining the work profile, the first cam device displacing the vertical carriage with the cutter spindle during cutting, the second cam device displacing the horizontal carriage and the third cam device turning said sleeve chuck, an adjusting device comprising a rotatable ring having lineal graduations and indicating the eccentricity of said spindle, a second rotatable ring having circular graduations, and a third ring keyed to the last mentioned ring and having a division indicating the position of the point of culmination relative to the said eccentricity, the several rings being mounted on the cutter spindle.
2. In a cam controlled milling machine of the

kind described, a horizontal work supporting carriage, a vertical carriage, a cutter spindle, a sleeve chuck eccentrically mounting the cutter spindle on the vertical carriage, and first, second and third cam devices for determining the position of the cutter spindle with respect to the work piece at any stage for defining the work profile, the first cam device displacing the vertical carriage with the cutter spindle during cutting, the second cam device displacing the horizontal carriage and the third cam device turning said sleeve chuck, a control device comprising an additional cam, a drum for rotating the spindle, spring means acting on said drum and a steel band wound on the drum and unreeling therefrom against the tension of said spring means under the control of said additional cam.

3. In a cam controlled milling machine of the kind described, a horizontal work supporting carriage, a vertical carriage, a cutter spindle, a sleeve chuck eccentrically mounting the cutter spindle on the vertical carriage, and first, second and third cam devices for determining the position of the cutter spindle with respect to the work piece at any stage for defining the work profile, the first cam device displacing the vertical carriage with the cutter spindle during cutting, the second cam device displacing the horizontal carriage and the third cam device turning

10

5 the control of said additional cam, and reverse gearing interposed between said drum and said spindle for determining the direction of rotation of the latter.
